UNITED STATES PATENT OFFICE

135,618

DESIGN FOR A TALC CONTAINER OR THE LIKE

Frank McIntosh, New York, N. Y., assignor to
Letheric, Incorporated, New York, N. Y., a
corporation of New York

Application January 6, 1942, Serial No. 105,038

Term of patent 3½ years

To all whom it may concern:

Be it known that I, Frank McIntosh, a citizen
of the United States, residing at New York city,
in the county of New York and State of New
York, have invented a new, original, and ornamental
Design for a Talc Container or the like,
of which the following is a specification, refer-
ence being had to the accompanying drawing,
forming part thereof.

Fig. 1 is a top plan view of a talc container or
the like embodying my new design;

Fig. 2 is a front elevational view; and
Fig. 3 is a rear elevational view thereof.

The dominant feature of the design consists
in the combination of a general prismatic con-
tour having oblong rectangular axial and trans-
verse sections, with corner flutings of quadrant
section, as shown.

I claim:

The ornamental design for a talc container or
the like, substantially as shown and described.

FRANK McINTOSH.
